(57) **CLAIM**

The ornamental design for a bioreactor as shown and described.

DESCRIPTION

FIG. 1 is a first perspective view of a bioreactor showing our new design;

FIG. 2 is a second perspective view thereof;

FIG. 3 is a third perspective view thereof;

FIG. 4 is a fourth perspective view thereof;

FIG. 5 is a fifth perspective view thereof;

FIG. 6 is a sixth perspective view thereof;

FIG. 7 is a seventh perspective view thereof;

FIG. 8 is an eighth perspective view thereof;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a cross-sectional end view taken along line 15-15 in FIG. 12 with the interior mechanism omitted;

FIG. 16 is a cross-sectional end view taken along line 16-16 in FIG. 12 with the interior mechanism omitted;

FIG. 17 is a cross-sectional end view taken along line 17-17 in FIG. 9 with the interior mechanism omitted; and,

FIG. 18 is a cross-sectional end view taken along line 18-18 in FIG. 9 with the interior mechanism omitted.

The broken lines in the drawings illustrate portions of the bioreactor that form no part of the claimed design.
